UNITED STATES PATENT OFFICE.

SAMUEL G. GREEN, OF CAMP BENNING, GEORGIA, AND JULIAN S. HATCHER, OF ANNAPOLIS, MARYLAND, ASSIGNEES TO UNITED STATES MACHINE GUN COMPANY, OF BOSTON, MASSACHUSETTS, A CORPORATION OF MASSACHUSETTS.

GUN MOUNT.

Application filed November 6, 1922. Serial No. 599,433.

This invention relates to gun mounts and more particularly to gun mounts for anti-aircraft guns.

The invention and its aims and objects will be clearly understood from the following description, taken in connection with the accompanying drawings, of various illustrative embodiments of the invention, the invention in its true scope being more particularly pointed out in the appended claims.

In the drawings:

Fig. 1 is a side elevation of a gun mount embodying one illustrative form of the invention;

Fig. 2 is a top plan view of the construction shown in Fig. 1;

Fig. 3 is a side elevation of the construction shown in Fig. 2;

Fig. 4 is a section on line 4—4 of Fig. 2;

Fig. 5 is a section on line 5—5 of Fig. 4;

Fig. 6 is a top plan view of the tripod;

Fig. 7 is a detailed section on line 7—7 of Fig. 4;

Fig. 8 is a section on line 8—8 of Fig. 1;

Fig. 9 is a top plan view of a gun mount embodying certain features of the invention;

Fig. 10 is a side elevation of the construction shown in Fig. 9;

Fig. 11 is a sectional elevation on line 11—11 of Fig. 9;

Fig. 12 is a sectional elevation on line 12—12 of Fig. 10;

Fig. 13 is a side elevation of another illustrative embodiment of the invention;

Fig. 14 is a top plan view of the construction shown in Fig. 13;

Fig. 15 is a section on line 15—15 of Fig. 14;

Fig. 16 is a section similar to that of Fig. 15 showing the adapter in use;

Fig. 17 is a section on line 17—17 of Fig. 16; and

Fig. 18 is a side elevation of the adapter.

Referring to the drawings the gun mount comprises gun carrying means and supporting means therefor, said gun carrying means and supporting means being connected by means to permit manipulation of the gun to train it upon the target, which term herein is intended to include any object to be fired at. In the embodiment of the invention here described the gun carrying means comprises a head 2 and the supporting

means comprises a standard or support 4. 55 The means connecting these two parts for permitting manipulation of the gun to train it upon the target, herein comprises a sphere 6 provided on the top of the standard 4 and preferably formed integral therewith. This 60 sphere 6 is received within a spherical socket formed in the head 2, which latter for convenience of assembly is preferably formed of two parts 8 and 10 provided with flanges 12 and 14 respectively, secured together by 65 screws 16. All of the above parts are of metal, any suitable metal or alloy being used for the purpose.

The lower section 10 of the head is provided with a slot 18 which is also continued 70 into the upper section 2 of the head for a certain distance as shown in Fig. 4 at 20. As shown most clearly in Figs. 4 and 5, the standard 4 extends through this slot 18.

From the construction above described, it 75 will be apparent that the head 2 is capable of unlimited swinging movement upon the sphere 6 about a training axis, herein a vertically positioned axis, and that said head is also capable of swinging movement about 80 any one of a plurality of elevating axes, herein horizontal, all intersecting said vertical axis centrally of the sphere 6, this swinging movement about any one of the elevating axes being herein preferably limited by 85 the end walls 22, 24 of the slot 18. The width of the slot 18 is such that its side walls engage the sides of the standard 4, so that tipping or swinging movement of the head 2 transversely to the slot 18 is 90 prevented.

As will be hereinafter more fully described, the gun or guns are carried by the head 2 in a plane or planes parallel to the plane of Fig. 4, the gun or guns pointing to the right, referring to said figure. From the movement permitted the head 2 about the two axes, as above described, it results that the gun or guns can be swung horizontally and vertically so as to be 100 trained upon the target. It will be noted that the slot 18 is of sufficient extent to enable the gun or guns to be swung upwardly into a substantially vertical position and downwardly at an angle sufficient 105 to cover ground within a very short distance of the gun. This wide sphere of possible operation is particularly valuable when

operating against aircraft or upon uneven ground, such as hillsides or the like.

The standard 4, by its cooperation with the side walls of the slot 18 prevents tipping of the carrier laterally, so that if the gun is secured to said carrier in a vertical plane, it will always be maintained therein.

The gun carrier will preferably be integral with the head 2. In Figs. 1, 2 and 3 a construction is shown having two such gun carriers 26, 26. These are herein located one at each side of the head 2. The carriers comprise side walls 28, 30, between which the gun is laid, substantially as shown in Fig. 1, the muzzles of the guns pointing to the right in Fig. 2. The guns rest upon the transverse pieces 32, 32 and each is provided on its under side with a downwardly projecting portion 34 (see Fig. 12), provided with holes to receive bolts 36, 36, preferably of the character shown in Fig. 12. These bolts are provided with a down-turned handle 38 and pass freely through one wall of the carrier, but have a screw-threaded connection at their ends with the other wall of the carrier, as shown in Fig. 12. Any other suitable means may be used to secure the gun in position upon the carrier, without departing from the spirit of the invention, but the above has proven itself extremely practicable.

A sighting tube 40 of usual construction is mounted between the two carriers 26, 26, as shown in Figs. 2 and 3, said tube being herein secured to brackets 42, 42 carried in any suitable manner by the head 2. This sighting tube constitutes common sighting means for the two guns, which are suitably positioned with relation to said tube to enable them to be trained by means of the latter upon the same target.

The gun shown in Fig. 1 in position on the gun mount is a machine gun, to which the cartridges are fed by a belt. When guns of this character are used with the mount shown in Figs. 1, 2 and 3, containers for the loaded belt are provided, one of such containers being preferably carried by each of the carriers at the outer side of each gun. Herein in said containers are in the form of boxes 44, one of which is shown in Fig. 1, and in part in Fig. 2. These boxes are preferably removably secured to the mount. This may be done by any suitable means, the means herein used consisting of two longitudinal ribs 46, 46, secured to a supporting member 48 and having inturned edges 50, 50 adapted to engage slots provided in the opposed walls of the boxes 44, as shown in Fig. 2. The members 48 may be rigidly secured to the mount, but herein they are preferably pivoted thereto at 52, so that the boxes may be swung out of operative position when not in use, the free ends of the supporting members 48 being provided with

a projecting tongue 54 which engages a slot provided in a member 56 projecting laterally from the front portion of the carrier, a spring latch 58 secured to the front wall of the carrier snapping over said tongue when it engages said slot, and holding the box in operated position.

Where the machine guns used are of a type in which the belt is fed into the left side of the gun, a guide will preferably be provided to guide the belt from the box 44 over the gun located upon the right side of the mount, referring to Fig. 2, so that the belt may readily enter the left side of the gun. Such a guide may be of any suitable construction, but herein consists of a plate 60 secured to the member 48 and extending upwardly and inwardly toward the carrier, as shown in Figs. 2 and 3. This guide rises to sufficient height to guide the belt over the gun and is provided with a rear flange 62, to assist in guiding the belt.

In Figs. 9, 10 and 11 the mount embodying our invention is shown adapted for a single gun. The ball and socket joint or connection is the same as that previously described, and the means for securing the gun on the carrier is also the same. The cartridge box 44 is conveniently mounted, in the manner described in the previous instance, upon the head at the opposite side of the ball and socket joint to that upon which is mounted the carrier.

In Figs. 13 to 16 is shown a mount embodying our invention adapted to carry two guns. In this illustrated form of our invention the ball and socket connection is also the same as that previously described, the head 2 being provided with a frame comprising the parts 64, 66, 68, 70 and 72. All of these parts are preferably integral. The two carriers comprise the cross-pieces 74, 74 upon which the guns rest in recesses 76, 76. Swinging clamping members 78 are pivoted at 80 to the frame and are provided at their free ends with slots 82, 82 adapted to be engaged by swinging clamping screws 84, which are normally swung outwardly, but when the clamping members 78 are swung down into position, are swung inwardly to engage the slots 82 and are then screwed down tight to hold the guns in place. The sighting tube 40 mounted between the two guns is similar in construction and operation to that already described.

The mounts described are adapted to receive guns of various sizes. In some cases the diameter of the gun, particularly at the barrel portion, may vary considerably with different sizes. In such case means are provided to enable the gun to be firmly clamped in place despite this variation. Any suitable means may be used for this purpose, said means herein comprising a semi-circular member 86, shown in detail in Fig. 18. 132

When a gun is of such small diameter to require it, the member 86 is inserted between the clamp and the gun as shown in Fig. 16.

While for illustrative purposes machine guns have been shown in Figs. 1, 2 and 3, and in Figs. 9 and 10, and automatic rifles have been shown in Fig. 13, it will be apparent that machine guns and automatic rifles may be used interchangeably on any of our 10 mounts, which are adapted to any kind of gun. It will also be apparent that our invention is applicable to mounts for carrying more than two guns, these being suitably arranged on the mount.

15 The gun mount embodying our invention will preferably be mounted upon a tripod, but it may be mounted upon any suitable support. When not mounted upon a tripod, the standard 4 may be inserted in any convenient aperture in any object suitable to support the gun, such as a gun-carriage, or wall, or part of a fence, for example, from which the gun may be operated. For convenience of insertion the lower end of the 20 standard 4 will preferably be pointed, as shown in Fig. 13.

In Fig. 1 the gun mount is shown as mounted upon a tripod. To this end the standard 4 is inserted within a tubular member or post 88 in which it can telescope, and in which it is securely held by a removable pin 90, see Fig. 7, which is adapted to fit in a hole extending through the standard 4 and through registering perforations in the side 30 walls of the tubular member 88. The perforation in one of the side walls of the tubular member 88 is provided with a downward extension 92, with which a tongue 94 on the pin 90 may be brought into registration. 35 About the hole provided in the standard 4 to receive the pin 90 there is provided an annular recess 96 at that end of the hole at which the pin 90 enters, as shown in Fig. 7. When the handle of the pin 90 is in the dotted-line position shown in Fig. 7, the tongue 40 94 registers with the opening 92, and by pushing the pin 90 inwardly the tongue 94 may be caused to pass through the opening 92 and into the annular recess 96, whereupon, by turning the pin 90 into the full-line position, for example, shown in Fig. 7, the pin will be locked in position by the tongue 94, and the standard 4 will be firmly held within the tubular member 88.

45 Upon the tubular member or post 88 there is slidably mounted a sleeve 98, to the lower part of which the three legs 100, 102, 104 of the tripod are pivoted at 106. Intermediate their ends the three legs of the tripod are 50 pivotally connected to the central tubular member 88 by links 108. The sleeve 98 has a sliding fit upon the tubular member 88 and is provided with a hollow boss 110 within which the wall of the sleeve is cut away. 55 Into one end of the circular bore of the boss

there fits a member 112 shaped upon one side to fit the contour of the tubular member 88, and provided at its front end with a screw-threaded pin 114. Into the other end of the circular bore of the boss 110 there fits a second member 116, also cut away at one side to fit the contour of the tubular member 88. This member 116 is provided with a perforation through which extends the pin 114. A head 118 is provided with a screw-threaded bore to enable it to be screwed upon the screw-threaded end of the pin 114.

If the head 118 be screwed down upon the member 116 it will draw the members 112 and 116 together, firmly clamping the sleeve 98 in adjusted position upon the tubular central member 88. By variably adjusting the sleeve 98 upon the central post 88 the legs may be spread more or less, as desired. The connection of one of the links 108 with one of the legs is preferably made adjustable lengthwise said leg, as shown in Fig. 1. As shown in said figure, the sleeve 120, to which one end of the link 108 is connected, has a sliding fit upon the leg 100 90 and is provided with a boss and clamping means which may be similar to that shown in Fig. 8 and used for the sleeve 98. This construction enables the mount to be tipped upwardly or downwardly at one side when 95 necessary.

When two guns are used means are preferably provided to stop the empty cartridge shells as they are ejected from the gun which discharges its empty shells toward the other gun. If such means are not provided the empty cartridge shells might impinge upon the other gun or some part of the mount and cause injury thereto and also possibly to the operator. Any convenient 100 means may be used for this purpose, but we have found that a piece 124 of flexible material, such as leather, suspended between the guns opposite the discharge opening of the gun in question, will arrest the ejected 105 empty shells and cause them to fall to the ground harmlessly.

The gun mounts embodying our invention possess many advantages over those heretofore used. The whole structure, and particularly the tripod is very sturdy and offers a very rigid and steady support for the gun. The provision of the pointed standard 4 enables the gun mount to be used upon any temporary support of suitable strength, providing a suitable opening is or can be provided therein to receive the standard. The joint used enables the gunner to train quickly upon any object, and if the object is in movement, such as an aeroplane, for example, to keep the gun trained thereon without difficulty. Experiments have shown that the barrel of a gun mounted on our gun mount can be caused to follow any line, 115 no matter how irregular it may be, and this 120

without any jerking or irregular movement, but in a perfectly steady line. This we attribute to the fact that the two axes about which the guns can swing, intersect, so that 5 the swinging movements about the two axes take place about a single point, namely the point of intersection of said axes, instead of about two separate points, as is the case where the two axes permitting a substantially universal movement of the gun, do not intersect. Where such intersection of the two axes does not take place, the movements about the two axes are more or less distinct and do not merge into a smoothly 10 executed resultant, as is the case with our invention. The gun can be swung in an entire circle horizontally, and upwardly into a substantially vertical position, and downwardly into a position to cover ground close 15 up to the implantation of the gun. The co-operation of the standard with the slot prevents tipping of the gun carrier transversely to the slot, so that, when the rifle or rifles are once properly adjusted in a vertical 20 plane in the carrier, they and the means used for sighting them will be maintained in such position, thus avoiding inaccurate shooting due to inclination of the rifle or its sighting means laterally out of the vertical. The means for stopping the ejected 25 empty cartridge shells is very efficient and avoids accidents. A multiple gun mount having a common sighting means for training all of the guns simultaneously upon the 30 target offers the advantage not only of enabling the operator to deliver a greater weight of metal than can be delivered by a single gun in the same space of time, but also enabling him to use one gun to get on 35 the target by firing tracer bullets from the gun, and then open up on the target with the other gun or guns. In this way much ammunition can be saved, while with a single gun using one tracer bullet for every 40 ten or so ball cartridges, as is usual, the waste of ammunition before getting on the target is often great. Other advantages will 45 suggest themselves to those skilled in the art.

It will be apparent that it is not indispensable that all of the features of the invention be used conjointly, since they may be used to advantage separately in various 50 combinations and sub-combinations. It will also be understood that, while the invention 55 is herein described as embodied in the details illustrated, it is not to be considered as circumscribed by or limited to these details, or any of them, but that said details may be variously modified within the true 60 scope of the invention which is definitely set forth in the claims.

Claims:

1. In a gun mount, in combination, a support; a sphere carried by said support; a 65 socket provided with a spherical chamber

slidably embracing said sphere; gun carrying means carried by said socket; a slot provided in the wall of said socket; a part of said support to engage said slot for rotary movement of said socket about the axis of 70 said part and for sliding movement of said part in said slot.

2. In a gun mount, in combination, a support; a sphere carried by said support; a socket having a spherical chamber slidably 75 embracing said sphere; a slot provided in the wall of said socket; a part of said support to engage said slot for rotary movement of said socket about the axis of said part and for sliding movement of said part 80 in said slot; means to position said slot in a vertical plane; and gun carrying means carried by said socket and adapted to carry a gun with its sights in a plane parallel to that of said slot. 85

3. In a gun mount, in combination, a support; a sphere carried by said support; a socket provided with a spherical chamber slidably embracing said sphere; a slot in the wall of said socket; means cooperating with 90 said slot to prevent movement of said socket about said sphere transversely to said slot, said socket being movable about the axis of said means and the axis of the sphere directed perpendicularly to the plane of said 95 slot; and gun carrying means carried by said socket and spaced from the axis of said means.

4. A gun mount comprising in combination, gun carrying means comprising a 100 sphere and a socket provided with a spherical chamber slidably embracing said sphere; a support therefor; a slot provided in the wall of said socket; means cooperating with said slot to prevent relative movement of 105 said socket and sphere transversely to said slot, said socket and sphere being relatively movable about the axis of said means and the axis of the sphere directed perpendicularly to the plane of said slot, said axes constituting the training axis and the elevating axis respectively; means to position said training axis in a vertical plane; and means to support a gun on said gun carrying means with its front and rear sights in a plane 110 parallel to said training axis. 115

5. A gun mount comprising in combination, gun carrying means comprising a 120 sphere and a socket provided with a spherical chamber slidably embracing said sphere; a support therefore; a slot provided in the wall of said socket; means cooperating with said slot to prevent relative movement of said socket and sphere transversely to said slot, said socket and sphere being relatively 125 movable about the axis of said means and the axis of the sphere directed perpendicularly to the plane of said slot, said axes constituting the training axis and the elevating axis respectively; means to position said 130

training axis in a vertical plane; means to support a plurality of guns on said gun carrying means, in spaced relation to said training axis and each with its front and rear sights in a plane parallel to said training axis; and common sighting means for said guns.

6. A gun mount comprising in combination, gun carrying means comprising a sphere and a socket provided with a spherical chamber slidably embracing said sphere; a support therefor; a slot provided in the wall of said socket; means cooperating with said slot to prevent relative movement of said socket and sphere transversely to said slot, said socket and sphere being relatively movable about the axis of said means and the axis of the sphere directed perpendicularly to the plane of said slot, said axes constituting the training axis and the elevating axis respectively; means to position said training axis in a vertical plane; means to support two guns, on said gun carrying means, in spaced relation to said training axis at opposite sides of said training axis and each with its front and rear sights in a plane parallel to said training axis; and common sighting means for said guns.

7. In a gun mount, in combination, a support; a sphere carried by said support; a socket provided with a spherical chamber slidably embracing said sphere; a slot provided in the wall of said socket; means cooperating with said slot to prevent movement of said socket about said sphere transversely to said slot; said socket being movable about the axis of said means and the axis of the sphere directed perpendicularly to the plane of said slot; and gun carrying means carried by said socket.

8. A gun mount comprising in combination, gun carrying means comprising a sphere and a socket provided with a spherical chamber slidably embracing said sphere; a support therefor; a slot provided in the wall of said socket; means cooperating with said slot to prevent relative movement of said socket and sphere transversely to said slot, said socket and sphere being relatively movable about the axis of said means and the axis of the sphere directly perpendicularly to the plane of said slot, said axes constituting the training axis and the elevating axis respectively; means to position said training axis in a vertical plane; means to support two guns, on said gun carrying means, in spaced relation to said training axis at opposite sides of said training axis and each with its front and rear sights in a plane parallel to said training axis; common sight-

ing means for said guns; and cartridge supplying means located at the outer sides of said guns.

9. In a gun mount, in combination, a gun carrier; a support therefor comprising a tripod and a central standard; links pivotally connecting the legs of said tripod and said standard; and means to adjust the point of connection of the link which connects said standard to one of the tripod legs longitudinally of the latter.

10. In a gun mount, in combination, a support; a sphere carried by said support; a socket provided with a spherical chamber slidably embracing said sphere; gun carrying means carried by said socket; a slot provided in the wall of said socket; means associated with said support to engage said slot for rotary movement of said socket about the axis of said means and for sliding movement in said slot; the construction and arrangement being such that said socket is movable only about the axis of the sphere coincident with the axis of said slot-engaging means and about the axis of the sphere directed perpendicularly to the plane of said slot.

11. In a gun mount, in combination, a support; a sphere carried by said support; a socket provided with a spherical chamber slidably embracing said sphere; gun carrying means carried by said socket; a slot provided in the wall of said socket; means associated with said support to engage said slot for rotary movement of said socket about the axis of said means and for sliding movement in said slot; the construction and arrangement being such that said socket is simultaneously movable only about the axis of the sphere coincident with the axis of said slot-engaging means and about the axis of the sphere directed perpendicularly to the plane of said slot.

12. A gun mount comprising in combination, gun carrying means comprising a sphere and a socket provided with a spherical chamber slidably embracing said sphere; a support therefor; a slot provided in the wall of said socket; and means cooperating with said slot to prevent relative movement of said socket and sphere transversely to said slot, said socket and sphere being relatively movable about the axis of said means and the axis of the sphere directed perpendicularly to the plane of said slot.

In witness whereof, we have signed our names to this specification.

SAMUEL G. GREEN.
JULIAN S. HATCHER.

CERTIFICATE OF CORRECTION.

Patent No. 1,621,365.

Granted March 15, 1927, to

SAMUEL G. GREEN ET AL.

It is hereby certified that error appears in the printed specification of the above numbered patent requiring correction as follows: Page 1, line 79, for the word "positioned" read "positionable"; page 4, line 121, claim 5, for the word "therefore" read "therefor"; and that the said Letters Patent should be read with these corrections therein that the same may conform to the record of the case in the Patent Office.

Signed and sealed this 19th day of April, A. D. 1927.

Seal.

M. J. Moore,
Acting Commissioner of Patents.
